ATTORNEY

UNITED STATES PATENT OFFICE.

ARTHUR DONALD CASWELL, OF MINNEAPOLIS, MINNESOTA.

TARGET CARRIER.

Application filed February 7, 1928. Serial No. 252,610.

This invention relates to improvements in target supports especially adapted for rifle and pistol practice, an object being to provide means for supporting a target so that 5 the latter will be held free from vibration.

Another object of the invention is the provision of means for supporting a target spaced from the firing point and in such a manner as to be adjustably positioned, or conveniently 10 moved to and from the firing point for examination or change of target.

With the above and other objects in view, the invention further includes the following 15 novel features and details of construction, to be hereinafter more fully described, illustrated in the accompanying drawings and pointed out in the appended claim.

In the drawings:—

Figure 1 is an elevation of the invention. 20 Figure 2 is an enlarged fragmentary section through one end of the target support.

Figure 3 is a detail end view of the target carrier with the target suspended therefrom.

Figure 4 is an end view of the supporting 25 member or upright at the firing point.

Figure 5 is a fragmentary end view of the upright or support at the opposite end.

Figure 6 is an enlarged horizontal section 30 taken through the support at the firing point and showing the cartridge shelf in plan.

Figure 7 is a detail elevation of a modified form of target hanger.

Figure 8 is a similar view showing another 35 form of hanger.

Referring to the drawings in detail wherein like characters of reference denote corresponding parts, the invention comprises a pair of spaced uprights or standards indicated at 10 and forming one of the supporting 40 members of the device, these uprights being provided with braces 11 which, together with the uprights, may be embedded in a concrete or other foundation. The uprights 10 are connected by a horizontal bar 12 and as the 45 device is designed to be made of pipe sections and fittings, the bar 12 is connected to the uprights by T's 13.

Spaced from the uprights or supporting members 10 is an upright or supporting member 14 whose lower end is suitably anchored to the floor and whose upper end is suitably anchored to the ceiling of the room or gallery within which the apparatus or device is arranged. The support 14 is positioned at the 50 firing point while the supports 10 occupy a position at the butts.

Secured to the supporting members is a track which is shown in the form of a wire or cable 15. One end of this wire or cable is secured to an eye bolt 16 which is carried 60 by the support 14 while the opposite end of the cable is secured to an eye bolt 17. This last mentioned eye bolt is secured within an opening provided in a T 18 which is included in the cross bar 12. The bolts 16 and 17 may 65 be adjusted to keep the cable in proper taut position, or, they may be removed for the removal and replacement of the cable.

Mounted upon the cable is a carrier 19. This carrier is also preferably made of pipe 70 sections and fittings and comprises an elongated member 20 which has centrally arranged therein a T 21, while at each end of the member 20 is an elbow 22. Extending from these elbows are yokes 23 which receive 75 the cable 15 and mounted in these yokes are grooved wheels 24 which ride upon the cable. Coupled to the T 21 is a T 25 which has removably and threaded secured in its lower end a hanger 26. This hanger is provided 80 with a spring clip 27 to engage a paper or other target 28 so that the latter will be suspended from the carrier. If desired, an elongated carrier 26^a may be substituted for the carrier 26, or a carrier 26^b may be utilized. 85 This last referred to carrier includes spaced arms 29 which engage adjacent opposite edges of the target instead of centrally as shown in Figure 3 of the drawings.

Mounted upon the supporting member 10 90 are spaced grooved pulleys 30, and passing around these pulleys is an operating cable 31. This cable also passes over grooved pulleys 32 secured to the upright 14 and around a grooved wheel 33 also secured to the upright 95 14. This wheel carries an operating handle 34 and its shaft or axle 35 is mounted in bearings provided in a coupling 36 which is included in the supporting member 14. The opposite ends of the cable 31 are secured to 100 the carrier 19 as shown at 37, so that by operating the wheel 33, the carrier may be moved longitudinally of the cable 15 from one end of said cable to the other, or may be adjustably positioned throughout the length of the 105 cable. By this means, a target may be moved to the firing point for inspection or renewal when desired.

Extending from the carrier 19 is a tubular member 38 whose outer end is beveled or 110 pointed as shown at 39. This tubular member 38 carries a lug 40. The cable 31 passes

through the tubular member 38 and through a tubular member 41 which is carried at the lower end of an arm 42, the latter extending downwardly from the bar 12. The member 41 is of greater diameter than the member 38 and is provided with a flared entrance 43 to receive the pointed end 39 of the member 38. As the carriage is moved outward or toward the supporting member 10, the tubular member 38 will enter the tubular member 41 and as the latter is provided with an elongated slot 44 to receive the lug 40, the carriage 19 will thus be held against lateral movement and vibration of the target will be prevented. The tubular member 41 also acts to limit movement of the carriage in one direction.

Extending from the supporting member 14 near the bottom thereof is a rifle support 45. This support is designed to receive the barrel of the rifle with the butt of the rifle resting on the floor. This keeps the rifle secure and free from damage. Extending from the upright or supporting member 14 immediately adjacent the pulley 33 is a shelf 46 which is designed to support cartridges for use by the user of the target.

The invention is susceptible of various changes in its form, proportions and minor details of construction and the right is herein reserved to make such changes as properly fall within the scope of the appended claim.

Having described the invention what is claimed is:—

A target support comprising spaced supporting members, a movable carrier, a target removably secured to the carrier, means secured to the supporting members to support the carrier for movement, an operating cable, means upon the supporting members to support and guide the cable, a horizontally disposed stationary slotted tubular member carried by one of the supporting members, a tubular member extending from the carrier for engagement within the stationary tubular member to limit movement of the carrier longitudinally of the carrier support, and a lug extending from the tubular member of the carrier for engagement within the slot of the stationary tubular member to prevent lateral swinging movement of the target.

In testimony whereof I affix my signature.

ARTHUR DONALD CASWELL.
